UNITED STATES PATENT OFFICE.

WALTER J. SMART, OF NEW YORK, N. Y.

APPARATUS FOR PURGING GUNS.

1,160,778.

Specification of Letters Patent.

Patented Nov. 16, 1915.

Application filed September 27, 1910. Serial No. 584,023.

To all whom it may concern:

Be it known that I, WALTER J. SMART, a citizen of the United States, residing in the city of New York, borough of Manhattan, county and State of New York, have invented certain new and useful Improvements in Apparatus for Purging Guns, of which the following is a full, clear, and exact specification.

10 This invention relates to ordnance and the art of operating the same and has for its object to provide an improved method of and apparatus for purging guns, particularly large guns, of the products of combustion 15 and of the burning or unconsumed portions of powder and powder container remaining in the chamber and bore after a discharge, for extinguishing fire in the chamber and bore of the gun, and for cleansing the surfaces of these portions of the gun, between 20 its discharge and the opening of the breach. Some fluid, which in practice may possess fire extinguishing qualities, such for instance as steam or carbonic acid gas, will be admitted to the chamber at its extreme rear 25 and forced over the rear wall of the chamber and past the corner formed by the juncture of the side wall of the chamber with its rear wall, through the chamber and from the 30 chamber through the bore and out of the muzzle. When the fluid employed is a fire extinguisher it will extinguish whatever fire may be present, blow the unconsumed portions of the powder and powder sack out of 35 the gun, and blow the smoke and gases out of the muzzle. When the breech is then opened there will be no escape of smoke or gas behind the gun and no flareback. This fluid will so have cleansed the gun that it 40 will be in proper condition to receive its next charge. The breech may be opened not only with perfect safety to the gunner but with comfort as well. The flareback and premature explosions are positively prevented thus 45 assuring safety to the gunner and to the equipment. Smoke and gas are not discharged behind the gun, which discharge is not only uncomfortable and injurious to the gunner, but also impairs his efficiency.

50 There generally is a steam plant in the fort or battleship, and this will be conveniently used in some cases. Compressed air will have sufficient pressure or force when liberated at the extreme base of the breech to tear loose any unconsumed rags sticking to the chamber as well as to expel all flame and gas.

After the shot is expelled by the pressure

of the gas the base of the gun will remain full of slowly burning gas since the only inlet for air is at the muzzle. When the gunners open the breech it is possible for a gust of wind to blow this flame back to the gun deck, and some fluid suitable to expel this smoke and flame will be employed. The fluid may be an extinguisher of such flame 65 and is liberated under such pressure as to force everything out of the muzzle.

In applying my improvements to the gun the cleansing fluid may be admitted without in any manner weakening the parts of the 70 gun. The fluid will be admitted through the mushroom head without changing in any way the working portion of such head or cutting or weakening the same.

My improvements may be applied to existing types of gun without changing the form of the parts. In some forms of gun considerable pressure will be required to move the mushroom head forward to permit the fluid to enter the gun.

80 The drawings accompanying and forming a part of this specification represent one form of a practicable embodiment of my improved apparatus and which may conveniently be employed in practising my improved method and in which drawings,

85 Figure 1 represents a longitudinal section of the rear portion of a gun, and, Fig. 2 a rear elevation of the parts shown in Fig. 1.

90 So much only of a gun is illustrated as is necessary to show the manner in which my improvements may be employed in connection with a gun and especially how it may be employed in connection with existing types of gun without materially changing 95 the parts thereof.

100 The breech block 5 is shown mounted in closed position in the breech 6 of the gun. Which block will close the chamber 7. And which block will be operated in whatever manner the particular style of gun to which the invention is applied will require.

105 The breech block is shown carrying the usual form of mushroom head 8 which head normally has a certain amount of longitudinal movement relative to the breech block. Behind the mushroom head and between the forward end of the breech block is shown a pair of plates 9, 10. Between which plates is a soft washer 11 forming a gas-check for 110 the purpose of making a gas tight joint upon pressure within the chamber. The stem 12 of the mushroom head 8 moves through the plates 9, 10, and the compres-

sible disk 11 and also through a bore in the breech block. An adjustable collar 13 is mounted upon the stem 12 and carries a flexible washer 14 which engages the walls 5 of the chambered out portion 15 of the breech block. This washer 14 is carried between a flange of the collar 13 and an adjustable ring 16. The head and stem are shown provided with the usual firing tube 10 17. The stem is hollow and provided with screw threads 18 for connection with a suitable source of fluid supply.

A spring 20 is shown interposed between the collar 13 and the front of the chamber 15 for drawing the mushroom head against the rear wall of the chamber, in the present instance the flange portion 21 against the plate 9. This will act as a closure for the ports 19 from the hollow stem. Behind the mushroom 20 head the stem 12 is provided with a series of openings 19 so that after the gun has been discharged fluid may be admitted through the hollow stem 12 to the chamber of the gun. Upon the fluid passing out of 25 the passages 19 it will force the mushroom head forward into the dotted line position 80 and the fluid will then violently pass over the face of the plate 9, which is in reality the rear wall of the chamber, and be directed 30 into the corner formed by the juncture of such rear wall with the side wall of the chamber, and then through the chamber and bore of the gun to and out of the muzzle thereof, driving before it smoke, gas, un- 35 consumed portions of powder and remnants of the powder container or sack, extinguishing any fire which may be within the gun, quenching the heat engendered by the previous discharge of the gun, and cleaning from 40 the surface any deposit which may have been made thereon during the discharge. By this means the gun is put into such condition immediately upon its discharge that the breech block may be opened with safety 45 and comfort, and the gun will upon its opening be in condition to receive another charge. The fluid will be admitted at the proper time either automatically or manually as the exigencies of the various situations may demand. 50 Although I have specifically mentioned by name a few fluids which are useful in practising my invention it will be perfectly obvious that others may be employed and although I have shown one illustrative embodiment of the apparatus it is also obvious 55 that changes can be made within the scope of my invention.

Having thus described my invention what I claim and desire to secure by Letters Patent is:

1. In a gun the combination with a breech

block having a bore and a chamber at its rear side, of a mushroom head, a hollow stem carrying said head and mounted in said bore, a collar having a flange mounted on 65 said stem within the said chamber, said collar being screw threaded at the side beyond the flange, a flexible washer mounted on said collar, and a split screw collar mounted on the said screw threads, and a bolt for holding 70 said collar in position.

2. In a gun flushing device, a breech-plug, a gas check, a mushroom head provided with a part spaced from the gas check to provide a chamber, an obturator spindle provided with a passage extending therethrough, a passage leading from the obturator spindle passage to the chamber between the mushroom head and the gas check, means for movably mounting the obturator spindle in 75 the breech-plug, said means normally holding the mushroom head against the gas check so that fluid under pressure passing through the obturator spindle will be admitted to the chamber between the mushroom head and the gas check in order to advance the mushroom head to allow the fluid 80 to pass therearound to flush the gun.

3. In a gun, a breech plug, a gas check, a mushroom head, an obturator spindle, a pressure chamber between the mushroom head and the gas check, a fluid inlet extending from the rear of the breech communicating with said fluid chamber, means coöperating with the obturator spindle normally 95 holding the mushroom head against the gas check so that the fluid under pressure admitted to said chamber will advance the mushroom head and pass therearound to flush the gun.

4. In a gun, a breech plug, a gas check, a mushroom head, an obturator spindle, means coöperating with the obturator spindle for normally seating the mushroom head against the gas check, gun flushing instrumentalities 105 comprising a pressure chamber beneath the mushroom head, one wall of the chamber being formed by the gas check, a fluid pressure inlet passage leading from the rear of the breech plug communicating with said 110 chamber whereby the fluid under pressure entering said chamber will cause the mushroom head to unseat from the gas check to permit the fluid to enter the bore of the gun.

In witness whereof I have hereunto set my hand in the presence of two subscribing witnesses.

WALTER J. SMART.
